D. J. McCARTHY

ADJUSTABLE ELECTRIC LAMP SUPPORT

Original Filed April 28, 1921

Inventor:
Daniel J. McCarthy

By Force, Beam & Hastings

UNITED STATES PATENT OFFICE.

DANIEL J. McCARTHY, OF ELGIN, ILLINOIS, ASSIGNOR TO CHICAGO RAILWAY SIGNAL & SUPPLY COMPANY, A CORPORATION OF ILLINOIS.

ADJUSTABLE ELECTRIC-LAMP SUPPORT.

Original application filed April 28, 1921, Serial No. 465,143. Divided and this application filed January 16, 1922. Serial No. 529,434.

To all whom it may concern:

Be it known that I, DANIEL J. McCARTHY, a citizen of the United States, residing at Elgin, in the county of Kane and State of Illinois, have invented certain new and useful Improvements in Adjustable Electric-Lamp Supports, of which the following is a specification.

This invention relates to adjustable electric lamp supports.

It will be explained as applied to a signal lamp wherein it is utilized in properly positioning and holding a lamp relative to the focus of a signal lamp lens system.

15 A method of adjusting original and replacement lamps and wherein this support may be used is claimed in my copending application Serial No. 465,143; filed April 28, 1921, of which this application is a division.

20 In many fields, such for example as railway signalling, it is often desirable and necessary to position electric lamps in a particular position relative to the foci of lens and reflector systems. Many of the signals must be placed in relatively inaccessible or difficultly accessible positions, such as the tops of poles, switches, signal towers, etc. The accurate replacement of burned out and defective lamps in such situations is sometimes impossible and always difficult and expensive. Laboratory methods in the field are out of the question.

25 One of the objects of this invention is to provide an improved adjustable support for electric lamps for signal and similar purposes.

Another object is to provide a support whereby the position of a lamp relative to the focus may be quickly and reliably adjusted.

30 Another object is to provide a support which may be readily operated to give accurate adjustment even in relatively inaccessible and difficult positions.

Another object is to provide a support which is reliable, inexpensive and efficient.

Other objects and advantages will hereinafter appear.

35 An embodiment of the invention is illustrated in the accompanying drawing, wherein the support is shown in position in a double lens lamp and cooperating with a

focus finder by means of which the source of light may be readily positioned in proper relation to the lenses.

The views in the drawing are as follows:

Fig. 1 is an elevation of a rear view of a light unit showing the focus finder in place thereon.

Fig. 2 is a vertical section taken on line 2—2 of Fig. 1.

Fig. 3 is a view similar to Fig. 2, showing a fragment thereof.

Fig. 4 is an enlarged sectional view of a part of the lamp adjusting support taken on line 4—4 of Fig. 2.

Fig. 5 is a similar view to Fig. 4 taken on line 5—5 of Fig. 2.

Fig. 6 is a section of part of the focus finder taken on line 6—6 of Fig. 2.

Fig. 7 shows a view in side elevation of the conventional filament of an electric lamp.

Fig. 8 is a diagram of the focus finder with the lamp displaced, on the focal axis and forward of the focal point.

In all the views the same reference characters are employed to indicate similar parts.

To obtain the highest efficiency in the projection of light by lenses, reflectors, or the like, it is quite essential that the source of light, such as the filament of an electric lamp, be placed at the exact focal point of the projector; when this has been achieved the light may be made, by use of a proper arrangement of lenses, to produce a beam of light in which the rays are in parallel lines, thus projecting a more intense and far reaching beam of light. By moving the lamp along the focal axis of the light projector towards the projector the rays may be made to outwardly diverge or flare while if the lamp be moved out of the focal point in the opposite direction the rays of light may thus be made to converge.

In railway signal systems, in different situations, the signal lamp units are required to project beams of light in which the rays are parallel; in other locations the rays of light must be diverging so as to extend over a relatively large light field at the objective point, and in others the light beam must be more concentrated at the point of applica-

tion. For uniformity of apparatus and economy of equipment, it is highly desirable that a single structure be made capable, by proper adjustment, to meet the various requirements of use.

It is furthermore necessary to be able to ascertain and to note the extent to which the field of illumination is extended or contracted, that is, the measure in degrees of digression from a beam of parallel rays. The instrument herein disclosed and the method of its operation is intended more particularly for readily establishing the filament of a new electric lamp in a lamp unit, in precisely the same location of the filament of the lamp initially installed in the unit, whereby it will produce the same results as the latter, although it may vary in some of its structural features or other characteristics from the original lamp.

The drawings show portions of a more or less conventional signal lamp unit in which 10 is a part of the unit casing providing a ring 11 for a lens 12, and a ring 13 for a lens 14. In this doublet arrangement of lenses, when the filament 15 of the electric lamp is located at the precise focal point, as shown in Fig. 2, the rays of light projected therefrom will form a beam in which the rays will extend in parallel lines. If the light point 15 be brought nearer to the smaller lens, the light beam will be more or less fan shape and if it be moved in the opposite direction, the beam of light will be concentrated.

A means for moving the lamp and securing it in its desired position is accomplished by the following instrumentality.

A bracket 17 carries lamp sockets 18 and 19, the lamp 16 is shown inserted in the latter, and is the active lamp of the unit. Socket 18 may be used to hold an extra lamp to replace the active lamp in socket 19, should the same be broken or burned out. The bracket is carried by or is part of a tube or sleeve 20, which is threaded at one end, as at 21.

A rotatable shaft 22 carries at one end an eccentric 23 to which it is fixed thru the annular sleeve 23'; at its other end it is fixed to an eccentric 25 by a pin 26. These eccentrics form journals upon which the shaft is rotatably supported and while they are shown to be somewhat different in diametric dimensions, the throw or eccentricity of the two eccentrics is the same so that, they act as one eccentric and upon rotation, the shaft 22 will be moved in parallel lines around the axis of its movement. The shaft and sleeve 23' are provided with a screw driver slot 27 for convenience of rotation or they may be rotated by a wrench engaging the annular sleeve 23'. The eccentric 25 is rotatable freely in a socket 28 which is a fixed part of the frame 10. To retain the

eccentric 25 in the socket it is provided with a groove 29 into which a screw 30 projects from the socket 28.

The eccentric 23 is rotatable in a ring 31 which is part of a rearwardly extending arm 32, which also carries the eccentric bearing or socket 28. Arm 32 is bifurcated at its inner end providing supplementary arms 33 and 34 fixed to the frame 10 by screws 35.

A tube or sleeve 36 overlies a large portion of shaft 22 and is freely rotatable with respect thereto. It is provided with an axially parallel slot 37 into which a screw 38, from the bracket sleeve 20, projects to permit the latter sleeve to be axially moved thereon and to cause said sleeves 20 and 36 to be rotated as one.

A nut 39, rotatable on the sleeve 36, is prevented from being axially moved thereon by a screw 40, which extends therefrom into an annular groove 41 in the sleeve. The sleeve 36 is normally held in fixed position with respect to the frame 10 by a set screw 41' which passes thru a hub 42 of sleeve 23'. The screw 41' is held in clamping position by a nut 43. The eccentric 23 is fixed by a set screw 44 which passes thru the hub 45 of ring 31, which is a part of the frame 10. A check nut 46 securely holds the clamping set screw 44 in clamping position.

From the above description it will be manifest that the lamp 16 may be moved to any desired point in a plane transverse to the focal axis of the lens combination by rotation of the shaft 22 and its connected eccentrics and that it may also be moved along the focal axis by rotation of the nut 39 and fixed in its adjusted positions by the set screws 41' and 44.

At the time when the light signal unit is assembled, a lamp 16 is placed in the socket 19 and its filament energized. The filament is then placed approximately at the focal point of the lens combination.

The beam of light from the outer lens is now measured photometrically. The lamp and filament are then movably adjusted and readings taken from the photometer until the exact focal point has been thus ascertained, whereupon the shiftable parts of the lamp adjusting device are locked in fixed positions by the set screws. Of course, if it is desired to have the signal unit project a flaring beam of determined degree the lamp and filament are adjusted accordingly. Any suitable method and apparatus for photometric calibration and measurement may be used.

After the lamp signal unit has been installed in service, it sometimes happens that a new electric lamp must replace the original, and the filament of the new lamp must occupy the same position as that of the original electric lamp.

The original shop method of finding the desired location or focal point, can not be pursued for placing a new lamp because the unit is supported on a pole or other inaccessible location and for this reason it is impractical or impossible to follow the original procedure outlined above.

I have therefore provided a focus finder and a method for reestablishing the initial relation with a substitute electric lamp and its associated lenses.

The instrument consists of a small closed casing 50 having an observation aperture 51. A portion of its edge wall is incurved, as at 52, the curved portion extending something more than 90 degrees and having portions of its wall inclined at 45 degrees from the perpendicular, as at 53 and 54. A small lens 55 is secured in an opening in the curved portion 52 of the housing wall vertically above the filament in said curved wall just 90 degrees removed. A light reflector 57 is secured to the wall 54, inclined just 45 degrees from the focal axis of the lens 55. A similar mirror or reflector 58 is fixed in the same manner to the inclined wall 53 and inclined 45 degrees from the focal axis of the lens 56 so that the beams of light reflected from the mirrors or reflectors 57 and 58 will be in planes precisely 90 degrees in angular relation to each other.

A plate of ground glass 59 is placed in the path of the beam 60 of reflected light and located at right angles thereto, upon which to receive the image 15^a of the lamp filament 15.

A plate of ground glass 61 is placed in the path of the beam 62 of reflected light from the lens 56 and located at right angles thereto, upon which to receive the image 15^b of the lamp filament 15.

A reflector 62' is placed over the plate 61 and inclined substantially 45 degrees so that an observer looking thru the aperture 51 will see the two reflected images 15^a and 15^b as they appear in Fig. 1, when the lamp filament 15 is in the position occupied by the original lamp which is the focal point of the lens combination.

The plates 59 and 61 each have a longitudinally extending central line 63 which blend into the line 63^a as they appear to the observer in Fig. 1. They each have a transversely extending line 64 and 65, respectively. When the images 15^a and 15^b are symmetrical with respect to the associated transverse lines and with respect to the single vertical line 63^a, as shown, the former relations of the light point of the lamp and lenses have been reestablished and the signal unit will operate with the new lamp in the manner as before its original lamp became defective.

Should adjustment be required to produce divergence of light rays of 5 degrees, 10

degrees or 15 degrees as exigencies of the case may require, at the field of illumination, means are provided for accurately ascertaining the degree to which the light beam will be laterally extended.

Fig. 8 shows the filament 15 moved toward the lens on the focal axis so that the angle of the light beam 60 is raised above the line 65, in a manner clearly apparent, in which event the image 15^a will be raised to the short lines 5, 10 or 15, according to the degree of beam expansion, on the plate 59, shown more clearly in Fig. 1—indicative of the respective degrees to which the light beam has been spread by the forward movement of the lamp 16.

Since, in the above example, the lamp is moved along the focal axis of the lens, there will be no disturbance of the light projected thru lens 56; therefore the image 15^b will remain on cross line 64.

To adjust the instrument 50 to a lamp signal unit in which the electric lamp has been located, in the manner heretofore described, so that it may be removed and subsequently replaced with accuracy, the casing 50 has projecting forwardly therefrom a tapered stem 66, having a transverse notch 67 in its smaller free end. At approximately the proper position in the frame 10 a socket 68 is made, which is considerably larger than stem 66. A sleeve 69, the bore of which is tapered to neatly fit the stem 66, has one or more grooves 70 and a transverse pin 71 which the transverse notch 67 of the stem 100 engages to prevent rotation of the stem and attached instrument.

When the filament 15 has been properly located by adjustment of the instrument the latter is fixed and temporarily held, with the stem 66 and sleeve 69 in the socket 68, and with the image 15^a and 15^b, as shown in Fig. 1. Then metal such as Babbitt metal, zinc or lead, 72, is poured into the socket and around the sleeve 69 to hold the latter in place in the socket. The instrument will now visually show the true focal point of the lens, and may be removed and reinserted for subsequent use.

The instrument may advantageously be used in connection with a parabolic reflector, or other reflector.

Having described my invention what I claim as new and desire to secure by Letters Patent, is:—

1. In a device for adjusting the position of a lamp, a rotatable shaft; two like eccentrics one on each end thereof; a tube rotatable on said shaft; a lamp bracket carried by the tube; means to move the tube and lamp bracket axially of the axis of the tube; means to lock the tube and shaft together to prevent relative rotation; and means to lock the shaft and tube to a fixed part of the structure.

2. In a device for adjusting the position of a lamp, a rotatable shaft; an eccentric secured to each end of the shaft to provide journals for the shaft; fixed bearings in which the eccentrics are rotatable, respectively; a tube rotatable on the shaft; a threaded sleeve axially movable on said tube and rotatable therewith; a lamp; a socket to receive the lamp carried by said sleeve; a nut engaging said sleeve to move it, said 10 socket and lamp axially of the tube; and means to lock said shaft tube and sleeve to prevent their rotation.
- In testimony whereof I hereunto set my hand.

DANIEL J. McCARTHY.
